US00D744636S

(12) **United States Design Patent**
Sanders et al.

(10) **Patent No.:** **US D744,636 S**
(45) **Date of Patent:** **** Dec. 1, 2015**

(54) **SPACER FOR INHALER**

(71) Applicant: **Clement Clarke International Limited**,
Harlow, Essex (GB)

(72) Inventors: **Mark Sanders**, Dunstable (GB); **David Spencer**, Harlow (GB); **Ronald Bruin**, Harlow (GB)

(73) Assignee: **Clement Clarke International Limited**,
Harlow, Essex (GB)

(**) Term: **14 Years**

(21) Appl. No.: **29/457,737**

(22) Filed: **Jun. 12, 2013**

(30) **Foreign Application Priority Data**

Feb. 14, 2013 (EM) 002184200-0001
(51) **LOC (10) Cl.** **29-02**
